UNITED STATES PATENT OFFICE.

HENRY WATSON WEATHERS, OF AUGUSTA, GEORGIA, ASSIGNOR OF ONE-HALF TO
JULIA MELVILLE DOUGHTY, OF AUGUSTA, GEORGIA.

PORTABLE CRANE.

Application filed January 22, 1926. Serial No. 83,041.

This invention relates to cranes.

The essential object of this invention is to provide a simple and inexpensive crane, which may be utilized in garages to elevate 5 the front or rear ends of automobiles, so as to make the under parts thereof readily accessible.

The crane is also well adapted for the loading of automobiles in box cars, in loading 10 automobiles in freight cars they are loaded sometimes three and sometimes four to the car. Where the shipment is of three automobiles, two are loaded on four wheels while the third one has its front end elevated 15 against the end of the car, being held in position by chocks and blocks, as is customary. Where four are loaded the machines at opposite ends of the car have their front ends elevated, while the two central cars are loaded 20 on four wheels.

It has been found very difficult and rather 25 dangerous to lower these end cars to the floor level, since the ordinary jack is extremely slow and its use involves a risk to the workman and to the car. In transit the cars are supported by stout timbers, which must be removed when the jacks are placed in position and in the process of lowering, the jack support must be changed two or three times. 30 This necessitates considerable labor and very careful work on the part of the operators. It is therefore another object of this invention to provide a crane which is particularly 35 adapted for unloading automobiles from box cars.

Another and very important object of the invention is the provision of a crane having an extremely simple form of adjusting means whereby the same may be adjusted to any 40 height of freight car and whereby the lifted end of the automobile may be elevated to any height, within reason.

Another object of the invention is the provision of a portable crane of simple construction embodying means for changing the elevation of the point of support of the chain hoist.

Further objects will appear as the following specific description is read in connection 50 with the accompanying drawings, which form a part of the application, and in which:

Figure 1 is a perspective view showing the crane attached to and supporting the front end of an automobile in elevated position.

55

Figure 2 is a detailed side elevation of the crane with parts broken away to better illustrate the method of adjusting the chain hoists supporting arm.

Figure 3 is a perspective view of the chain 60 hoist supporting arm removed.

Figure 4 is an enlarged cross sectional view on the lines 4—4 of Figure 2, and

Figure 5 is a fragmentary rear elevation.

Referring now to the accompanying drawings in which like reference characters are applied to like parts throughout the views.

1 indicates a rectangular frame preferably made up of angle irons riveted together and suitably braced at their corner joints. This frame is supported upon castors 2 arranged beneath each of the four corners so that the frame may be moved over the ground or other support in any direction, either forwardly, rearwardly or laterally.

75

Rising from the frame 1 and secured to the side members thereof, slightly to one side of the longitudinal center, are inclined uprights or supports 3, which converge to a point 4 and then extend a further distance 80 in spaced parallel relation as shown at 5; these supports are braced against lateral movement and held in proper position by cross bars 6 and 7, and by diagonal struts 8, as shown. The supports 3 are also braced in 85 their inclined upright position by the vertical struts or braces 9, which are secured at their lower ends to the side bars of the frame 1 and converge to their point of attachment with the uprights 3, at a point 90 slightly below the point 4. These braces or struts 9 are riveted or spot-welded to the frame 1 and are similarly connected to the uprights 3. The uprights 3 may be also riveted, spot-welded or otherwise suitably connected to the frame 1.

95

In order to take care of the forward pull on the upper end of the uprights 3 and to further assist in bracing the same I secure to the rear portion of frame 1, at opposite 100 sides thereof, guy rods or bars 10, which are attached to the upper end of the uprights

3 by a through bolt 11 which has surrounding the same, between the uprights, a spacing sleeve 12 which serves in part to hold the part 5 in spaced relation.

- 5 Secured to the uprights 3 in any suitable manner, such as by riveting or spot-welding, is a bracket member 13 of U-shaped formation provided with a reduced loop 14 for a purpose to be hereinafter described. This 10 bracket preferably straddles the uprights 3 above the point 4 and serves with the sleeve 12 to hold the part 5 of the uprights in spaced parallel relation.

In cranes of this type a multiplying chain hoist is usually employed in connection with some suitable type of grapple, such for instance as illustrated in my Patent No. 1,555,725, granted September 29, 1925, and in order to support this chain hoist and grapple 15 in proper position to engage either end of an automobile or other article to be lifted, I provide an adjustable extension 15 here shown in the form of a flat bar approximately three-fourths inch by four inches in 20 cross section and preferably three or more feet in length, this bar is arranged to fit and slide between the parallel portion 5 of the uprights 3 and is provided with a series of diagonally positioned notches 16 throughout 25 a portion of its length and arranged in its front edge, and a central aperture 17 positioned in its forwardly extending end 18 when in position upon the uprights 3 or between the uprights 3, the extension 15 has 30 one of its notches 16 engaged over the sleeve 12 and its lower end engaged in the loop 14 of the bracket 13, in this position when weight is applied to the chain hoist, which is supported by the forwardly extending 35 end 18 the extension will fulcrum on the sleeve 12 and its lower end will engage the loop 14 holding it firmly in adjusted position. By changing the height of the extension, on the supports 3, the point of support 40 of the chain hoist may be regulated to suitable position.

From the foregoing it will be seen that I have provided a very simple and cheaply constructed crane which may be easily and rapidly adjusted to change the height of the point of support of the chain hoist, in this manner the lifted end of an automobile may be raised to any desired height or may be lowered from such height. The 50 fact that the crane is portable or movable in any direction makes it convenient to handle and if the end of the automobile which is being raised is chocked the crane will move toward the automobile as the end is being raised or away from the same as it is being lowered automatically.

While I have described one specific embodiment of my invention I desire it to be clearly understood that many changes and 55 modifications may be resorted to in practice,

which are not specifically covered by the foregoing description, but which fall within the terms of the appended claims.

In the claims I shall refer to the part 1 as a truck or possibly as a castered or 70 wheeled base, but wherever these terms are used I wish it understood that reference is made to the frame 1 or to the frame 1 and its supporting casters 2.

What I claim is:

1. In combination a wheeled base, uprights carried thereby, connecting means for said uprights and a grapple lift supporting member adjustably supported upon said connecting means whereby its point of support 80 may be raised or lowered and means for holding said member in rigid adjusted position when a weight is applied to said grapple lift.

2. In combination a wheeled base, braced 85 uprights thereon, means for holding the uprights in spaced relation, and a chain hoist supporting member adjustably supported on said spacing means, whereby the point of support of said hoist may be raised or 90 lowered.

3. In combination a wheeled base, braced 95 uprights carried thereby, means for connecting and holding the uprights in spaced relation, a chain hoist supporting member pivotally and adjustably mounted on said connecting and spacing means, and means for limiting the pivotal movement of said member.

4. In combination, a base having casters 100 thereon, braced converging uprights carried by said base, means for connecting said uprights in spaced relation, a chain hoist supporting member pivotally and adjustably mounted on said spacing means, and means carried by the uprights for limiting the pivotal movement of said member.

5. A portable crane comprising a base supported on casters for universal movement, an inclined upright secured to each 110 side of the base, said uprights converging toward their upper ends, means for connecting the upper ends of said uprights, a notched chain hoist supporting member adjustably mounted upon said connecting 115 means and having pivotal movement between said uprights, lifting means adapted to be connected to the upper end of said member, and means for limiting the direction of movement of the lower end of said 120 member.

6. A portable crane comprising a base supported on casters for universal movement, an inclined upright secured to each side of the base, said uprights converging 125 toward their upper ends, means for connecting the upper ends of said uprights, a notched chain hoist supporting member adjustably mounted upon said connecting means and having pivotal movement be- 130

tween said uprights, lifting means adapted to be connected to the upper end of said member, and a bracket secured to the uprights and adapted to limit the movement 5 of the lower end of said member.

7. A portable crane comprising a castered base, an inclined upright secured to each side of the base, braces connecting said uprights, braces connecting said uprights and said 10 base, means connecting the upper ends of said uprights, spacing means on said connecting means for holding the ends in spaced relation, a supporting bar for lifting means having a plurality of notches therein, said 15 bar adapted to be adjustably and pivotally engaged with said spacing means, and a yoke shaped bracket straddling the uprights and adapted to receive and limit the movement of the lower end of said bar.
- 20 8. In a portable crane, a rectangular frame supported upon casters, an inclined upright secured to either side of said frame, said uprights converging toward their up-

per end and then extending on in spaced 25 parallel relation, a through bolt connecting the upper ends of said uprights, a sleeve surrounding the bolt between the uprights for holding the same in spaced relation, a notched bar for supporting a lifting means, said bar having an aperture in its upper end 30 to receive a chain hoist hook or the like, said bar adapted to be adjustably and pivotally supported upon the spacing means, a yoke bracket straddling said uprights and serving to limit the movement of the lower end 35 of said bar, and struts connecting the through bolt and the frame.

9. In a crane, uprights, connecting means for said uprights, a hoist supporting element pivotally mounted on said connecting 40 means and means carried by the uprights for limiting the pivotal movement of the hoist supporting means.

In testimony whereof I affix my signature.

HENRY WATSON WEATHERS.
